LEVER ARM SCREW DRIVER AND WRENCH

2 Claims. (Cl. 145—76)

1

This invention relates to improvements in tools of the screw driver and wrench type and more particularly to a combination of such tools.

In using a screw driver it is necessary to steady the bit end with the fingers of one hand while applying the turning force to the handle with the other hand. This is particularly necessary when using the conventional straight bit screw driver. Other types of socket-head type screws are made in which the tendency for the tool to slip is eliminated, but it is still necessary to steady the bit end with the fingers of one hand.

In driving screws or plugs by means of a screw driver the diameter of the handle usually is such that when any great turning pressure is required, it becomes increasingly difficult to drive the screw or plug home as it should be. Very often when this condition arises a separate wrench is applied to the bit and the increased leverage utilized.

The disadvantage of using the conventional slot engaging screw driver is that frequently sufficient pressure cannot be applied to tighten a screw properly without utilizing an additional wrench and this usually results in a damaged screw slot.

The disadvantage of using a wrench with a screw driver for tapered socket screws is that the additional leverage cannot be utilized because of the tendency for the tool bit to cam out of the tapered socket.

The disadvantage of utilizing a wrench in which the leverage is applied by a longitudinally extending handle, is that the wrench is not steadied properly and in places where a complete revolution of the handle cannot be made, requires the disengaging and re-engaging of the bit in its recess each portion of a revolution. This consumes time and requires patience.

A further disadvantage is that the available wrenches may provide too great a leverage for the screw driver or screw resulting in structural failure and possible hazard to the operator of the tool.

I have therefore invented the combination screw driver and wrench which is disclosed here-with and which provides a tool that overcomes the above mentioned disadvantages. In addition a tool having a double action is provided, first in that a means is provided for rapidly starting a

2

screw into its threaded opening by means of a thumb and finger knob and second in that a wrench means is provided when additional power is required. In other words, with my combination tool a screw may be spun into its threaded opening as far as possible by means of a knob on the driver shank and then a lever is engaged and used as a wrench for the final tightening operation.

The principal object of this invention is to provide a combination driver tool and wrench in which the tool bit may be conveniently revolved by a wrench handle in which it revolves for the purpose of spinning screws and similar devices into accommodating threaded openings to a point where resistance becomes too great for finger operation, after which the wrench is made to engage the bit and the leverage of its handle utilized to continue the tightening operation to the desired point.

Another object is to provide a combination driver tool and wrench where the bit may be steadied by means of the wrench handle when the turning of the bit is by the driver knob and where the wrench handle is in turn steadied by the driver bit and knob when leverage is being applied by means of the wrench handle.

Another object is to provide a combination driver tool and wrench in which additional force can be applied to the tool bit, to retain it in the driver slot of a screw or like device, when the maximum turning force is applied thereto.

Another object is to provide a combination driver tool and wrench of this nature in which the wrench handle may be engaged or disengaged after turning the bit a portion of a circumference so that complete revolution of the bit may result from repeatedly engaging and disengaging the wrench handle when it is impossible to revolve the wrench handle completely because of interferences.

Another object is to provide a combination driver tool and wrench of this nature in which yieldable means are provided to maintain the bit in a position where it may be revolved without rotation of the wrench handle until the leverage of the handle is required.

Another object is to provide a combination driver tool and wrench in which the integral

wrench handle is limited to a length providing a turning force within the safe limits of the driven screw for the average applied manual force.

Another object of this invention is to provide a combination driver tool and wrench which can be used and stored like a conventional screw driver.

These objects and the several novel features of the invention are hereinafter more fully described and claimed and the preferred form of construction by which these objects are attained is shown in the accompanying drawings, in which:

Fig. 21 is a perspective fragmentary exploded view of the driving collar of the wrench illustrated in Fig. 20.

In the Figs. 1 through 5, the numeral 39 represents a driver tool of hexagonal or other irregular form integrally united to a shank 31 and stem

32. Shank 31 is cylindrical and provided with an annular groove 33 at the upper portion of its length. To stem 32 is tightly attached the knurled knob 34 for the purpose of turning tool 30 by means of thumb and finger. Surrounding shank 31 is a wrench head 35 which is integral with a leverage arm 36. Head 35 is provided with a round opening 37 for the accommodation of shank 31 and is of such fit that the latter revolves freely when knob 34 is rotated. For the purpose of yieldably maintaining the wrench arm in the position shown in Fig. 2 when the wrench portion is not being used for turning, I provide an opening 38 formed across opening 37 in such manner that a coiled spring 39 and a retaining ball 40 may be inserted in it to place pressure on the ball in groove 33. Head 35 is provided with a recess 41 of hexagonal or other irregular form to fit over the bit body 30 when engaging it as shown in Fig. 4. In this position the leverage of arm 36 may be applied to tool bit 30 with one hand while being steadied by the other hand grasping knob 34.

Fig. 2 illustrates the position of this tool when a set screw 42 is being screwed into member 43 by the turning of knob 34. In this operation the arm 36 is held steady and acts as a guide to hold the bit in place. This is especially desirable when the bit is of the form of the screw driver 44 in Fig. 6, as it holds the bit in its slot and is convenient in starting the screw straight in a member which should preferably have holes drilled if the member is of wood or tapped if of metal.

By applying pressure to knob 34, wrench recess 41 may be engaged with and disengaged from bit 30 quickly and due to its polygonal form the bit may be turned through a small portion of a full revolution, then disengaged, turned back and the amount of turn repeated somewhat similar to the result of ratchet wrench operation.

Fig. 3 shows how shank 31 revolves in the polygonal recess 41 when the wrench arm 36 is in the position of Fig. 2. When the wrench arm is needed for additional leverage, a slight pressure downward and a slight turning of the arm in relation to the bit permits the recess to surround the bit as shown in Figs. 4 and 5 so that leverage applied to arm 36 is transmitted to revolve the tool bit.

In running a screw or similar item into a member my combination driver tool and wrench is held in the position illustrated in Fig. 2 by means of arm 36 and the knob 34 is turned until screw 42 offers such resistance that it cannot be turned by thumb and finger any fur-

ther. Then the wrench is pressed lengthwise of the shank until recess 41 engages bit body 30 and the tightening process continued by utilizing the leverage of arm 36.

In removing a screw or similar item the wrench arm is used first and then disengaged from the bit so that the knob and bit may be spun in reverse.

A similar tool is illustrated in Figs. 8 through 13 in which I provide a wrench arm which is foldable for conventional operation or convenience in storing the tool. The numeral 50 represents a driver tool integral with a shank 51 and knob or handle 52. The cylindrical shank 51 is provided with annular grooves 53 and 54. Surrounding shank 51 is a wrench head 55 having a recess 64 of irregular shape and a U-shaped bracket 70 on which wrench arm 56 is pivotally supported at 57. The enlarged portion 58 of arm 56 serves as a bearing block and cam surface for co-acting with and retaining spring 60 in wrench head 55 as I will describe later.

Fig. 9 illustrates the folded inoperative position of wrench arm 56 in which its contoured portion 62 fits within the recess 61 of handle 52, shown by dotted line in Fig. 11, and serves to complement the driving tool handle 52 for convenience when the tool is used in the conventional manner. Arm 56 is yieldably maintained in this position, by spring 60, which serves the dual purpose of biasing arm 56 towards its folded position by means of its action on cam 59 and yieldably restraining its axial movement due to the engagement of its depressed tongue 63 with groove 54. Handle 56 is extended by grasping it above the bearing block with the thumb and forefinger and pivoting it away from the handle 52. A slight downward pressure will then cause it to assume the positions illustrated in Figs. 8 or 10.

Fig. 8 shows the wrench arm 56 extended with the wrench head 55 in the steadyng position in which it is used to guide the driving tool as it is rotated by means of handle 52. In this position the tongue 63 of spring 60 is engaging groove 53 to restrain the wrench head 55 from axial movement.

In Figs. 10 and 12 the wrench head 55 and its pivotal driving arm 56 are illustrated in the driving position in which the polygonal recess 64 of wrench head 55 surrounds its mating section on the bit 59 so that leverage applied to wrench arm 56 is transmitted to tool bit 59. In this position, arm 56 is maintained substantially rigid because tongue 63 of spring 60 is trapped between cam 59 and shank 51.

Fig. 13 further details the construction of the mating wrench head 55, the tool bit 59 and the method for retaining spring 60 in head 55. The wrench head 55 has the raised contoured edges 67 and 68 on which the bent extremities 65 and 66 of spring 60 bear to retain it in place and support it for its biasing action on cam 59 of handle 56. The opening 69 in support 55 permits the resilient tongue 63 of spring 60 to engage grooves 53 and 54 of shank 51 for the purpose I have previously described.

A similar tool, illustrated in Figs. 14 through 19, differs from the tool in Figs. 8 through 13 in that the wrench arm 76 is housed within the handle 72 as shown in Figs. 14 and 15. In this construction I have provided a simple wrench arm 76 which is adapted to be extended laterally for steadyng or driving the tool bit or slidably

retracted within the driving tool handle 72 for normal use or storing.

Fig. 19 details the position of wrench arm 76 prior to its insertion in chamber 71 of handle 72. With wrench head 75 in the illustrated position and the wrench arm 76 extended laterally, as in Fig. 17, the driving tool can be steadied in the manner of the previously described tools.

Fig. 17 shows the chamber 71 in handle 72 and the wrench head 75 in engagement with the tool bit 73 as is illustrated more clearly in Fig. 18.

A similar tool is detailed in Figs. 20 and 21 having a wrench head 85 with a lower castellated section 87 for engaging a pin 86 through the cylindrical shank 81 of the driving tool. In this novel variation the driving pin 86 serves also as a means of retaining the wrench head 85 on a shank 81 of uniform cross-section.

By "multi-sided," as used in the claims, is meant any formation wherein the male and female portions on the tool shank and lever collar, respectively, match but are so formed that when they are engaged with one another any relative angular, or rotative, movement between them is prevented.

In the above specification, I have described some modifications of my invention but it will be understood that further alterations could be made without departing from the spirit and scope of invention defined by the following claims.

I claim as my invention:

1. A tool having a handle and an aligned shank which terminates in a work-engaging end, said shank in the vicinity of said end, being formed with a multi-sided section and between said section and said handle being formed with spaced-apart annular grooves, a collar on said shank having a multi-sided socket for fitting over said multi-sided shank section, a lever pivotally connected to said collar so that it may lie alongside said shank or be swung to a position in which it extends at right angles with respect to said shank, and resilient means carried by said collar and which is engageable with one of said grooves to hold said collar against axial movement when said lever occupies said first mentioned position and which is engageable with the other of said grooves to hold said collar against axial movement in a position in which said lever may be extended to said second position to steady said work-engaging end while permitting said shank to be turned freely in said collar by said handle, said resilient means being operative in a third position of said collar in which said socket fits over said multi-sided shank section to lock said lever in its extended position against pivotal movement with respect to said collar.

2. A rotary driver of the character described having a handle and an aligned shank which terminates in a bit, said shank being formed in the vicinity of said bit with a multi-sided section and between the latter and said handle with upper and lower annular grooves, a laterally extending lever arm having a hub formed with a bore through which said shank extends, means pivotally connecting said lever arm and hub so that the lever arm may be folded toward said shank, and a spring-biased detent carried by said hub, said hub being adjustable lengthwise of said shank and being formed so that the lower end of said bore provides a multi-sided socket for fitting over the multi-sided section of said shank in one position of said hub to lock said

lever arm and shank against relative angular movement so that a rotative force may be applied to said shank by said lever, said hub being movable to a second position on said shank to disengage said multi-sided socket from said multi-sided shank section and in which position said detent engages said lower annular groove, whereby to enable said driver to be steadied by said lever arm while permitting said shank to be turned freely by said handle, said hub being movable to a third position in which said detent engages said upper annular groove to hold said lever arm in said folded position.
